UNITED STATES PATENT OFFICE

2,199,857

FLASH LAMP

Marvin Pipkin, Cleveland Heights, Ohio, assignor
to General Electric Company, a corporation of
New York

Application November 16, 1938, Serial No. 240,783

3 Claims. (Cl. 67—31)

My invention relates in general to flash lamps of the type used for photographic purposes which usually comprise a sealed transparent bulb or envelope containing a readily combustible material. More particularly, my invention relates to the envelope or bulb of such flash lamps.

At present, flash lamps generally comprise a sealed transparent bulb of clear glass in which is enclosed a readily combustible material, such as metal foil and/or wire, together with suitable ignition means therefor, and a combustion-supporting substance, usually a gas filling, which, upon ignition of the lamp, enters into a reaction with the combustible material with the resulting emission of actinic light.

Lamp bulbs as a rule do not have a uniform wall thickness. Flash lamps of the above-mentioned type develop internal pressure when flashed, and if there is a thin spot in the bulb wall it may give way, resulting in an explosion with consequent danger from flying fragments of glass. Accordingly, as a safeguard against such accidental explosions, it has been customary to provide the interior surface of the flash lamp bulb with a lacquer coating such as cellulose acetate, which is highly inflammable. This produces a clear film on the glass which serves to prevent shattering of the bulb upon flashing of the lamp, thus tending to render the bulb substantially shatterproof.

Due to a number of reasons, the protective lacquer coating frequently becomes either entirely or partially separated from the bulb wall. Thus, the heat attending the sealing-in operation of the lamp tends to shrink the lacquer coating so that it tends to separate from the bulb wall. The presence of water vapor within the sealed bulb likewise tends to separate the coating from the bulb wall. Then too, the leakage of air into the bulb through cracks in the lacquered portion of the bulb wall results in a separation of the coating from the bulb wall. In any event, the separation of the lacquer coating from the bulb wall gives rise to a dangerous condition, for the separated portion of the inflammable lacquer coating burns freely when the lamp is flashed, thus tending to increase the pressure developed within the lamp and frequently causing an explosion. Also, the hot molten particles of combustible material readily puncture the separated lacquer film and strike the uncovered glass of the bulb, thereby tending to crack the same and cause an explosion. The separation of the lacquer film from the bulb wall is difficult to observe so that the person flashing the lamp is

frequently unaware of its dangerous condition. According to the present invention, means are provided to materially impede or retard the tendency of the lacquer coating to loosen or separate from the bulb wall, but if such a separation actually should occur, a readily discernible indication thereof is promptly given.

One object of my invention is to provide a flash lamp bulb with a firmly adherent lacquer coating on a surface thereof, preferably on the inner 10 surface.

Another object of my invention is to provide a lacquered flash lamp bulb which will promptly give a readily discernible indication of any separation of the lacquer coating from the surface 15 of the bulb.

Still another object of my invention is to provide a flash lamp with safety means for positively indicating the leakage of air into said lamp through that portion of the lamp bulb actually 20 surrounding the combustible material within the lamp.

A further object of my invention is to provide an inside frosted flash lamp bulb having a coating of transparent lacquer on the frosted inner surface of said bulb.

Further objects and advantages of my invention will appear from the following description of a species thereof and from the accompanying drawing, in which Fig. 1 is an elevation, partly 30 in section, of a flash lamp comprising my invention; Fig. 2 is a fragmentary sectional view, on an enlarged scale, of the lacquered bulb wall portion of the flash lamp shown in Fig. 1; and Fig. 3 is an elevation of a flash lamp comprising 35 my invention showing the visible indication given when a portion of the interior lacquer coating becomes separated from the lamp bulb.

Referring to Fig. 1, the flash lamp according to my invention comprises a vitreous transparent envelope or bulb 10 containing a loose filling of combustible material 11, such as a filamentary wire of aluminum or its alloys, and a combustion-supporting gaseous filling, preferably oxygen. Mounted within the bulb 10, within effective ignition range of the combustible material 11, is a small filament 12 the ends of which are connected to leading-in wires 13, 13 which extend through a stem 14 to a conventional screw-threaded lamp base 15. The filament 12 is embedded in a bead 16 of fulminating substance to thereby form the ignition means for the lamp. An insulating disc 17, preferably of asbestos, is mounted on the stem 14 to shield the base end of the lamp from the heat of combustion.

As shown particularly in Fig. 2, the inner surface of the bulb 10 is frosted, preferably by etching, to thereby provide a roughened inner surface 18. This frosted surface is preferably produced 5 by the method disclosed and claimed in my United States Patent No. 1,687,510, issued October 16, 1928, although it may be produced by any other suitable method, such as by sand blasting. A thin coating 19 of a suitable clear lacquer, 10 preferably cellulose acetate, is applied over the frosted inner surface 18 of the bulb 10. The thickness of the coating may vary from 0.2 to 1 mil or thereabouts, but is preferably made 0.5 of a mil thick. The said coating 19 extends 15 down into the neck portion of the lamp bulb to a point just beyond the insulating disc 17. Because of the roughened inner surface 18, the lacquer coating firmly adheres to the bulb—much more so than is the case where the coating 20 is applied to ordinary untreated glass bulbs. As a result, the danger of explosions, which frequently occur on the flashing of a lamp having a portion of the lacquer coating 19 separated from the bulb wall, is practically eliminated. 25 The increased adherence of the lacquer coating to the bulb wall also materially reduces the number of lamps rejected during manufacture because of loosened bulb coatings. The lamp bulb has a distinctive appearance in that the coated 30 portion thereof has a clear glass appearance while the uncoated neck portion has the milky white appearance characteristic of frosted glass.

In addition to the above-enumerated advantages, safety indicating means are provided by 35 the invention whereby the presence of any loosened or unattached lacquer coating material, or the presence of air leakage into the bulb through the lacquered portions thereof, is positively and quickly indicated by the appearance 40 of a readily discernible spot, as shown at 20 in Fig. 3, of milky white appearance corresponding to that of a conventional inside frosted lamp bulb. This spot of contrasting appearance defines the area of the inner bulb surface from 45 which the lacquer coating has become loosened. When the clear cellulose acetate solution is applied to the inside frosted lamp bulb 10, the original milky white appearance of the frosted bulb immediately disappears and becomes sub- 50 stantially transparent or clear. Apparently, this is due to the filling up of the cavities of the frosted inner surface 18 of the lamp bulb and the resulting formation of a smooth interior surface which does not refract or diffuse the rays of 55 light passing through the bulb wall in the manner effected by the original frosted surface, but

instead transmits them substantially without refraction or diffusion. However, when any portion of the clear cellulose acetate coating loosens or becomes separated for any reason from the inner bulb surface 18, the uncovered surface of the bulb is again left free to refract and diffuse the light passing through that portion of the bulb. Accordingly, an area of milky white appearance, corresponding to the original frosted appearance of the bulb and defining the area 10 of the inner bulb surface from which the cellulose acetate coating has become separated, is instantly produced. This spot therefore serves to apprise one of the defectiveness of the lamp so that he will refrain from flashing the same 15 and thereby prevent injury to person and property which might otherwise result if the lamp were flashed and an explosion occurred.

In the appended claims, the expression "frosted inner surface" is intended to include all roughened glass surfaces which are similar to a surface frosted by etching, i. e., all surfaces having a multiplicity of minute pits or depressions. The term "lacquer" is also intended to include any similar protective coating material. Although 25 it is preferred that the inner surface of the bulb be frosted and coated, the outer surface of the bulb may, if desired, be frosted and coated.

What I claim as new and desire to secure by Letters Patent of the United States is:

1. A flash lamp comprising a glass bulb containing a combustible material and combustion-supporting means, said bulb having a frosted surface, and a protective coating of lacquer on said surface, separation of said lacquer coating 35 from said surface being indicated by a contrasting appearance of said surface from its normal appearance.

2. A flash lamp comprising a glass bulb containing a combustible material and combustion-supporting means, said bulb having a frosted inner surface, and a protective coating of lacquer on said inner surface, separation of said lacquer coating from said surface being indicated by a contrasting appearance of said surface from its 40 normal appearance.

3. A flash lamp comprising a glass bulb containing a combustible material and combustion-supporting means, said bulb having its inner surface frosted by etching, and a protective coating of cellulose acetate on said surface, separation of said cellulose acetate coating from said surface being indicated by a contrasting appearance 50 of said surface from its normal appearance.

MARVIN PIPKIN.
